(57) **CLAIM**

The ornamental design for a 3D front panel of a lock box, as shown and described.

DESCRIPTION

FIG. 1 is a perspective view of a 3D front panel of a lock box showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings represent portions of the 3D front panel of a lock box that form no part of the claimed design.
